Primary Examiner — Kevin K Rudzinski

(57) CLAIM

The ornamental design for a children's garment having a handle, as shown and described.

DESCRIPTION

FIG. 1 is a rear view of the children's garment having a handle;

FIG. 2 is a close-up rear view thereof;

FIG. 3 is a front view thereof;

FIG. 4 is a top view thereof;

FIG. 5 is a bottom view thereof;

FIG. 6 is a left side view thereof; and,

FIG. 7 is a right side view thereof.

The dashed lines showing the remainder of the garment are for environmental purposes only and form no part of the claimed design.

1 Claim, 4 Drawing Sheets
